**TAP-OFF CONNECTOR FOR UNDERGROUND
INSTALLATION OF ELECTRICAL SERVICE**

James Edward Warner, Mechanicsburg, Pa., assignor to
AMP Incorporated, Harrisburg, Pa.

Filed Aug. 5, 1968, Ser. No. 13,029

Term of patent 14 years

Int. Cl. D13—03

U.S. Cl. D26—1

FIGURE 1 is a perspective view of a tap-off connector for underground installation of electrical service;

FIGURE 2 is a top plan view of the connector of FIGURE 1;

FIGURE 3 is an elevational view of the connector of FIGURE 1;

FIGURE 4 is a left-hand end view of FIGURE 3;

FIGURE 5 is a right-hand end view of FIGURE 3;

FIGURE 6 is a bottom plan view of the connector of FIGURE 1;

FIGURE 7 is a perspective view of a modified form thereof, wherein the only difference resides in the location of the small rod element, as shown; and

FIGURE 8 is a perspective view of another modified form thereof, wherein the only difference resides in the location of the small rod element, as shown.

I claim:

The ornamental design for a tap-off connector for underground installation of electrical service, as shown and described.
